UNITED STATES PATENT OFFICE.

FRED K. MURPHY, ALBERT WM. MARTIN, AND LOUIS C. H. WEIDMAN, OF
INDIANAPOLIS, INDIANA.

PROCESS FOR RECLAIMING WORN CAR-AXLES.

1,366,922.

Specification of Letters Patent.

Patented Feb. 1, 1921.

Application filed June 21, 1919. Serial No. 305,852.

To all whom it may concern:

Be it known that we, FRED K. MURPHY, ALBERT W. MARTIN, and LOUIS C. H. WEIDMAN, citizens of the United States, and residents of Indianapolis, county of Marion, and State of Indiana, have invented a certain new and useful Process for Reclaiming Worn Car-Axles; and we do hereby declare that the following is a full, clear, and exact description thereof, reference being had to the accompanying drawings, in which like numerals refer to like parts.

This invention relates to a process for reclaiming worn car axles and one feature of the invention is in enlarging the journal bearing after it has become worn down to the point of becoming useless, by enlarging the diameter of the bearing surface of the journal to slightly greater than the initial dimensions thereof.

Another feature of the invention is in adding metal to parts of the journal by welding, upsetting, and expanding process, and increasing the thickness and diameter of the free end of the journal, these operations so increasing the dimensions of the worn parts, that when machined down, the parts of the journal will be the same in dimensions as when the axle was originally placed in use.

This means of reclaiming the axles greatly reduces the cost of upkeep and replacements as the expense and time required for treating the axles is reduced to a minimum, while the axle, after being treated, will be the same as new.

In the accompanying drawings, which are made a part of this application, Figure 1 is a plan view of one end of a car axle showing the same rough and unfinished. Fig. 2 is a similar view of the axle after it has become worn, showing the end thereof positioned in a die. Fig. 3 is a plan view of the end of the axle and the die after the axle has been upset to expand the journal portion thereof, parts of the axle and upsetting tool being shown in section. Fig. 4 is a plan view, partly in section, showing the journal end of the axle after it has been expanded with the metal to be added to the axle removed therefrom. Fig. 5 is a plan view of the mold and end of the axle showing the manner of applying the added metal to the end of the axle, parts of the axle and welding tool being in section.

Referring to the drawings, in which similar reference numerals designate corresponding parts throughout the several views, 1 indicates a car axle which may be of any preferred type having at each end thereof a seat 2 for the reception of the usual form of a car wheel, and beyond each seat is a journal or bearing 3 which receives the wear when the axle is in use. At the inner end of each journal is a shoulder 4 which is between the journal and the wheel seat 2, while at the outer end of the journal is a collar 5, said shoulder and collar serving to hold the axle against undue longitudinal movement in its bearings.

In use, the journals on the axle, together with the shoulders 4 and collars 5, become so worn as to render the axle useless, and heretofore it has been customary to replace the worn axles with new axles, but it has been found that by restoring the journal portion of the axle to its original size and shape that the life of the axle may be greatly prolonged, thereby greatly reducing the expense of renewal. To this end a die block 6 is provided in which is formed a die chamber 7, the outlines of which are substantially coincident to the outlines of the axle 1 in its original and unfinished state.

In treating the axle to upset or expand the journal portion thereof, one end of the axle is heated to a forging temperature and then introduced into the die, as shown in Fig. 2 of the drawings. A plunger or header 8 having a conical spud 9 on one end thereof is then driven into one end of the die chamber and into engagement with the outer end of the journal 3, the force of the blow driving the spud into the end of the journal, and owing to the heated condition of the metal, expanding the parts of the journal until they fit the outline of the die chamber thus restoring the diameter of the journal 3 as well as the dimensions of the shoulder 4, and in fact creating a slight excess of metal on these parts so that they can be machined down to the proper dimension.

To restore the collar 5 to its proper dimension a disk 10 of metal is added to the outer end of the journal 3, the inner face of the disk having a substantially conical shaped plug 11 thereon which fits the recess 12 in the end of the journal 3 formed by the spud 9 during the expanding operation, the thickness of the disk 10 being such as to

restore the collar 5 to substantially its normal thickness and width when the disk is attached to the end of the journal.

In applying the disk to the end of the journal the plug 11 is entered in the recess 12 and the end of the axle again subjected to heat and brought to a welding temperature, after which it is again placed in the die chamber 7. The disk 10 is then welded to the end of the journal 3 by delivering blows thereagainst with a plunger 13. The axle is then removed from the die and machined down until it is brought to the proper dimension, thereby producing as perfect an axle as when the axle was originally made, and this operation may be repeated.

This manner of treating the axles to restore them to their original condition may be accomplished at a minimum of expense, and at the same time a great saving in material is made as it has been customary in the past to junk such axles as they became worn, without attempting to restore them to their usefulness.

25 The invention claimed is:

1. The process of reclaiming worn car axles consisting in extending the journal portion of a car axle to its original bearing dimensions from the original journal stock

and adding metal to the non-bearing part of the journal to restore the journal portion of the axle to its initial dimensions.

2. A process for reclaiming worn car axles, embodying the heating of the journal ends of the car axles to a forging heat, 35 expanding the heated portion of the axle, applying additional metal to the end of the journal, subjecting the end of the axle and the added metal to a welding heat and then welding the added metal to the end of the 40 journal, the expanding of the journal and the addition of the metal restoring the journal portions of the axle to their initial dimensions.

3. The process of reclaiming worn car 45 axles, which process consists in heating the journal ends to a forging heat, expanding the same while heated by forming a recess in the ends thereof, filling said recesses with metal, and welding the added metal thereto 50 for restoring the parts of the journal to their initial dimensions.

In witness whereof, we have hereunto affixed our signatures.

FRED K. MURPHY.
ALBERT WM. MARTIN.
LOUIS C. H. WEIDMAN.
